United States Patent Office

Des. 193,992
Patented Nov. 6, 1962

193,992

DATA COLLECTOR CABINET

Henry H. Bluhm, Phoenix, Ariz., assignor to General Electric Company, a corporation of New York

Filed Aug. 11, 1961, Ser. No. 66,306

Term of patent 14 years

(Cl. D26—5)

FIG. 1

FIG. 2

FIG. 1 is a front three-quarter view of a data collector cabinet showing my new design.

FIG. 2 is a rear three-quarter view of same.

The essential features of my design reside in the portions shown in solid lines.

I claim:

The ornamental design for a data collector cabinet, as shown and described.
